HEAT RESPONSIVE WIRE CONTROLLED
OVERLOAD CIRCUIT BREAKERMorris B. Wood, Newburyport, Mass., assignor to Wood
Electric Corporation, Lynn, Mass., a corporation of
MassachusettsFiled Oct. 9, 1959, Ser. No. 845,387
9 Claims. (Cl. 200—116)

The present invention relates to improvements in electrical overload circuit breakers of the trip-free type, more particularly as described in a prior application for United States Letters Patent, Serial No. 786,644, filed January 13, 1959, in the name of the present inventor.

In inventor's prior application there is disclosed an easily manufactured compact construction contained within an insulating frame and provided with a bimetallic thermostatic latch employed as a current responsive breaker tripping device. It has long been the desire of circuit breaker manufacturers to avoid the use of bimetallic latches or thermostatic controls of similar nature for many reasons, not the least of which are their critical and delicate responsiveness to temperature change, their changeability in use and their difficulty in adjustment after assembly in a circuit breaker. Furthermore, bimetallic latches are generally known to provide extremely weak forces when heated or cooled, so that every mechanical advantage must be taken in the design of breakers employing them to free them of any possibility of simple frictional load, which would impede their effectiveness. The breaker of the prior application has been found to be of desirable construction in avoiding difficulties of this nature, especially for low current capacity circuit breakers and accordingly the present inventor has been encouraged to extend the design of the prior breaker to use with even more elemental, weaker forms of thermostatic latch, not employing bimetallic devices.

It is accordingly an important feature of the present invention to provide a simple inexpensive circuit breaker of the trip-free type disclosed in the prior application, above-identified, which is effective with overloads of low intensity and is not dependent upon a bimetallic latch such as required in the prior breaker. In this respect, a more specific object of the invention is to provide an improved trip-free low capacity circuit breaker, utilizing as its current responsive device a convenient arrangement employing a short length of electrical resistance wire.

To the extent outlined above, the invention at hand resides in a trip-free overload circuit breaker having an insulating frame, fixed and movable contacts in the frame; a support for the movable contact, a locked releasable member, a wedging member acting between the releasable member and the movable contact support and a detent engaged with the releasable member to lock it against separation from the movable contact support, in which there is provided a heat responsive wire stretched between the detent and the frame for restraining the detent in locking relation with the releasable member.

These and other features of the invention, as herein-after described and claimed, will readily be understood from the following detailed specification and drawings, in which:

FIG. 1 is a sectional front view of a trip-free, automatically reset circuit breaker embodying the features of the present invention, the contacts of the breaker being shown in closed relation;

FIG. 2 is a sectional plan view of the breaker, taken along the line II—II of FIG. 1;

FIG. 3 is a further sectional plan view of the breaker, taken along the line III—III of FIG. 1;

FIG. 4 is a sectional side view of the breaker, taken along the line IV—IV of FIG. 1; and

2

FIG. 5 is a sectional bottom plan view of the breaker taken along the line V—V of FIG. 1.

The trip-free overload breaker illustrated in the drawings is both manually operated to open and close a circuit to be protected and automatically operated in response to current overload to open the circuit and to prevent manual closure of the circuit until the conditions causing the overload are corrected. The breaker is also designed to reset itself automatically, so that it may be closed manually by a single downward movement of a circuit closing button. The mechanism for actuating the breaker is the same in many respects as that of the prior application, above identified, in that a locked releasable member, a movable contact actuating member or support and a wedging member connected to a manually actuated button are provided. To open the contacts the movable contact support is in the form of a resilient strip which is biased toward circuit opening position and is forced against its bias toward circuit closing position by the wedging member when the releasable member is locked.

Referring more particularly to the drawings, an insulating hollow frame will be seen at 10, the manual circuit closing button at 12, and the locked releasable member in the form of a cam lever at 14. The contact actuating strip at 16 is reversely bent, and the wedging member, to which the button 12 is connected, is shown at 18. The button 12 is slidably mounted in a collar formed in a plate 20 secured to the open upper end of the hollow frame 10 and movable along a central path between and parallel to the sides of the frame 10, being pressed manually downwardly to close the circuit through the breaker and pulled upwardly to open the circuit. Upon the occurrence of an overload in the controlled circuit the contacts are opened and the parts of the breaker are moved to reset positions, with the button 12 being moved upwardly to indicate an open circuit and to facilitate quick closing by a single downward movement when required. If however, the overload in the circuit persists or the closure is attempted too soon to permit a current responsive element to cool, the releasable member will be unlocked and the breaker held in open circuit position.

Instead of utilizing a bimetallic strip, as in the breaker of the prior application, as a thermostatic tripping device, the breaker of the present invention employs a heat responsive wire 22 of heat resistant alloy, such as stainless steel or even less expensive material of readily heat expandable composition. The wire 22 does not act directly on the locked cam lever, as is common practice with the use of a bimetallic strip, but a detent 24 is provided to lock the releasable lever 14 against separation from the movable contact actuating strip 16, when engaged by the wedging member 18, which is constructed from a pair of parallel plates (see FIGS. 3 and 4) fastened together in spaced relation by three rivets 26, 28 and 30. The rivet 26 extends beyond the plates forming the wedging member 18 to engage a pair of liners 32 held inside the front and rear walls of the frame 10 by recesses in the corners of the frame (see FIG. 4). The rivets 28 and 30 are headed at their ends against the plates of the wedging member and terminate just outside these plates to insure a rigid friction free construction.

To provide the proper action of the wedging member 18 the rivet 30 bears directly against a cam surface 34 on the edge of the releasable member and the rivet 28 passes through a roll 36 disposed between the plates. The roll 36 engages and rides along an intermediate portion of one arm of a spring strip 38, forming the resilient support for the movable contact, indicated at 40. The rivet 26 passes loosely through the lower end of the button 12 to form a pivotal connection therewith. When

the button is depressed the rivet 30 rides along the cam surface 34 of the releasable lever 14 and the roll presses the movable contact support to press the movable contact 40 against a fixed contact 42 on the right side of the frame, as shown in FIG. 1.

To insure reliable operation of the detent 24 in accordance with the temperature of the heat responsive wire 22 the wire is stretched under uniform tension between the detent 24 and a resilient clip 44 attached at one end to a terminal plate 46 inside the frame 10. The resilient clip has a free end secured to the lower end of the heat responsive wire, which extends in adjacent parallel relation with the left side of the frame as viewed in FIG. 1. The detent has a horizontal arm to which the upper end of the wire 22 is secured. Along a central portion of the detent it is provided with parallel flanges having narrow, edge opening recesses to fit loosely about a fulcrum pin 48 engaged at its ends in openings in the liners 32 between the front and rear walls of the frame.

At its lower end the detent 24 has an opening through which passes a projecting angular shoulder 50 on the releasable lever 14, the force of the releasable lever acting directly along the length of the detent on the fulcrum pin 48. The angle formed by the shoulder 50 is selected to provide a smooth quick release of the locked lever 14 by a wedging action of the lower end of the detent away from the locked lever 14, the heat responsive wire restraining the detent from displacement while the locked lever is locked.

Current flowing through the heat responsive wire 22 heats it and causes it to expand. When heated sufficiently the expansion of the wire 22 permits release of the shoulder on the locker lever 14 and the movable contact 40 separates from the fixed contact 42. As soon as the contacts separate the lever is turned in a counter-clockwise direction about a fulcrum pin 52, also engaged at its ends within openings in the liners 32 and held in position lengthwise by the front and rear walls of the frame 10. In turning about the pin 52 the cam surface 34 changes its angle and the force of the resilient movable contact support strip 16 presses the rivet 30 on the wedging member upwardly, shifting the wedging member bodily out from between the locked lever and the support 16. The button also moves upwardly to indicate an open circuit condition.

As soon as the releasable locked lever 14 is released and the wedging member shifted upwardly the released lever is reset. For this purpose the fulcrum pin 52 is surrounded at either side of the lever 14 by coils of a resetting spring 53 of hairpin shape engaging along its central portion the lever 14 and at its ends an internally projecting flange portion 54 on the frame. At the same time that the lever 14 is reset, the detent 24 relocks the lever. To relock the releasable lever 14 the detent 24 has near its upper end a centrally perforated leaf spring 56 fastened to it with the lower end of the spring slidably engaged with the left inner side of the frame. The wire 22 passes through the perforation in the leaf spring 56 and urges the detent into locking relation with the releasable lever.

The resilient contact support strip 16, the resetting spring 53 and the relocking spring 56 are graded as to forces of resiliency. The force of the strip 16 is the greatest and is capable of overpowering the two springs, the force of the resetting spring 53 next in resiliency and the relocking spring 56 is the weakest. If necessary, the clip 44 may yield sufficiently to permit the releasable lever 14 to be relocked by the detent 24, the clip maintaining the wire 22 under tension at all times.

To determine the position of engagement of the detent 24 with the shoulder 50 on the releasable locked lever 14 and consequently to adjust the sensitivity of the breaker the resilient clip 44 at its free end, to which the wire 22 is secured is engaged with an adjusting screw 58 threaded into the lower left corner of the frame. The

inner end of the screw 58 is engaged with the clip and the other end of the screw is exposed outside the frame to enable change in the relation of the detent and the releasable locker lever 14 without dismantling the breaker.

5 By mounting the detent 24 and the heat responsive wire 22 lengthwise along one side of the frame in adjacent parallel relation thereto and the reversely bent movable contact support in parallel relation to the detent and wire at the side of the frame opposite to the wire and 10 detent and with the wedging member and releasable lever mounted to act between the detent and the support, a compact and effective construction is provided.

The circuit through the breaker runs from the terminal plate 46 which extends through the bottom of the frame 10, the clip 44, wire 22, the upper end of the detent 24, a flexible lead 60 connected between the detent 24 and a threaded block 62, the movable contact support 16, contacts 40 and 42, and a terminal plate 64 clamped by screws 66 to the right side of the frame 10. The terminal plate 46 is clamped similarly to the bottom of the frame by screws 68 passing through the frame and into threaded engagement with the terminal plate 46.

15 The nature and scope of the invention having been set forth and an embodiment having been described it is intended to include within the confines of the invention all modifications and equivalents which fall within the scope of the appended claims.

20 What I claim is:

25 1. A trip-free overload circuit breaker having a frame, a fixed contact in the frame, a movable contact, a resilient support to which the movable contact is secured and mounted for movement toward and from the fixed contact, a lockable releasable cam member, a wedging member acting between the releasable cam member and the resilient support for engaging the movable contact with the fixed contact, and a detent engaged with the releasable member to lock said releasable cam member against movement under the influence of said resilient support when actuated by the wedging member, in combination with a heat responsive wire stretched between the detent and the frame for restraining the detent in locking relation with the releasable member when the heat responsive wire is cold and for freeing the detent from the releasable member when the wire is heated.

30 45 2. A trip-free overload circuit breaker, as in claim 1, in which there is provided a spring fastened to the detent for urging the detent into locking relation with the releasable member.

35 50 3. A trip-free overload circuit breaker, as in claim 2, in which there is provided a resetting spring connected to the releasable member to return it to locked position after the contacts are separated.

40 55 4. A trip-free overload circuit breaker, as in claim 3, in which there is provided a button connected to the wedging member for actuating it to open and close the contacts manually.

45 60 5. A trip-free overload circuit breaker, as in claim 1, in which there is provided a resilient clip in the frame with a free end secured to the heat responsive wire to maintain the wire under tension.

65 6. A trip-free overload circuit breaker, as in claim 5, in which an adjusting screw is threaded into the frame with one end engaged with the clip and the other end exposed outside the frame to enable change in the relation of the detent and the releasable member without dismantling the breaker.

70 7. A trip-free overload circuit breaker having a frame, a fixed contact in the frame, a movable contact, a locked releasable member, a wedging member to engage the movable contact with the fixed contact, and a detent engaged with the releasable cam member to lock said releasable cam member against separation from the wedging member, in combination with a heat responsive wire stretched between the detent and the frame in adjacent parallel relation to one side of the frame for retaining

the detent in locked relation with the releasable member when the heat responsive wire is cold and for releasing the detent from the releasable member when the wire is heated and a reversely bent resilient support, to one end of which the movable contact is secured in parallel relation to the wire and the other end of which support is fixed to the side of the frame opposite to the heat responsive wire.

8. A trip-free overload circuit breaker comprising: a fixed contact; a movable contact; a resilient support for said movable contact; a pivotally mounted releasable cam member; a detent; a heat responsive wire connected to said detent, said detent being adapted to restrain the movement of said pivotally mounted releasable cam member only when cold and to yield to said pivotally mounted releasable cam member when conditioned by a current overload; an operating member; and a wedging member carried by said operating member for acting between said cam member and said resilient support so as to close said contacts in response to movement of the operating member.

10

15

20

9. A circuit breaker according to claim 8 wherein said detent has a shoulder and said releasable cam member has a shoulder, said shoulders being normally interengaged for providing said restraint of the releasable cam member, and wherein rotation of the detent in releasing the restraining engagement of the releasable cam member positions said shoulders in wedging relation for smoothly moving said detent out of restraining engagement with the releasable cam member.
